UNITED STATES PATENT OFFICE.

ARMENIUS DAVIS, OF SHELBYVILLE, INDIANA.

IMPROVEMENT IN CANE-GUNS.

Specification forming part of Letters Patent No. **29,676**, dated August 21, 1860.

To all whom it may concern:

Be it known that I, ARmenius Davis, of Shelbyville, county of Shelby, and State of Indiana, have invented a new and useful Improvement in Cane-Guns; and I do hereby declare that the following is a full and exact description, viz:

The nature of my invention consists in providing a self-cocking secret lock with the cap-tube, also concealed in the upper end of a cane, so that nothing is to be seen but the finger-hold of the trigger; also, I use a light hollow iron tube for the walking stick or cane, and for a ferrule I have a peculiar metallic hand-hold for the ramrod, which serves that purpose, as I carry an extension-ramrod in the cane-barrel.

To enable others skilled in the art to manufacture and use my invention, I will now proceed to describe the same, both as to construction and operation, and I desire that the accompanying drawings and the letters of reference marked thereon shall constitute a part of this description, and in all cases like letters refer to similar parts.

Figure 1 is an elevated side section of my invention, in which nearly all its working parts are to be seen. Fig. 2 is a longitudinal view of my improved ramrod, and Fig. 3 shows the extension part of this ramrod.

A is the barrel or main body of my cane or walking-stick. It may be made of any length, and the bore of any caliber, although I prefer a large bore, so as not to have the cane too heavy. The barrel may be of steel or iron, and the bore may be smooth or rifled. This barrel screws fast to B, its breech, or the cane-handle, which may be crooked with a gradual curve, so as to render the disguise complete.

C is the trigger-handle, and this actuates the trigger-bar D. This trigger-bar has a small projection on its upper side, a, which actuates the straight horizontal hammer-bar F. The trigger is held close in the curve of B by the steel spring E, and when the trigger is pushed down toward the barrel (so as to engage with hammer F) this spring aids in pulling the hammer back.

G is the mainspring, which drives the hammer F. In hammer F a small click, b, actuated by a hair-spring, c, is adjusted at the right point to engage with the inclined projection a, so as to draw the hammer back.

By close observation it will be seen that the trigger-bar D and the hammer-bar F are set

at an incline one to the other, converging at their front ends. Now, when the finger is placed into the ring C and the bar D is pushed forward, the little projection a passes under the click b, (the click b rising up to allow its passage,) and the spring c forces the click down in the rear of said projection or catch. Now it (the trigger) is pulled back until this catch and the click are separated by the divergence of their respective bars, when the hammer F is disengaged, and is thrown by mainspring G against tube d with ample force to break the cap and discharge the load. There is a hinge, which is held by a slide-pin, that covers over the tube d, by simply raising which a cap can be placed on said tube at pleasure. The mainsprings E and G have friction-rollers at the points where most pressure is had.

H is the ferrule of the cane, and is likewise the handle for the ramrod I. This ferrule is fastened onto the muzzle end of the cane by the pin i, which works in an inclined spiral slot.

J, Fig. 2, shows the extension-rod, Fig. 3, drawn out to its utmost. e is the ramming-head of this extension-rod, while f is the pin that holds it out as seen in the groove at f', Fig. 2. This extension device can be made of any reasonable length by simply deepening the hole for its play in the end of the ramrod I and lengthening the slot for pin f to correspond. An offset is made in this slot at its end nearest the end of the ramrod, into which the pin f is turned when the extension, Fig. 3, is drawn out.

The advantage of this extension consists in, first, the ability of carrying your loading-stick always with you, and out of sight, and second, in the readiness with which you can always lengthen your stick without the usual cumbrous screw-joint, &c.

Having thus fully described my invention and its mode of operation, what I claim as new, and desire to secure by Letters Patent, is—

The arrangement and combination of straight percussion-bar F and trigger-bar D, when these are made with their various peculiarities, as shown, and operated as described.

ARMENIUS DAVIS.
